UNITED STATES PATENT OFFICE.

EMIL ANDERSON, OF NEW YORK, N. Y., ASSIGNOR TO THE UNIVERSAL TURBINE COMPANY, OF JERSEY CITY, NEW JERSEY, A CORPORATION OF NEW JERSEY.

TURBINE OR IMPACT-ENGINE.

1,271,825.

Specification of Letters Patent.

Patented July 9, 1918.

Application filed October 30, 1911, Serial No. 657,451. Renewed December 5, 1917. Serial No. 205,671.

To all whom it may concern:

Be it known that I, EMIL ANDERSON, a citizen of the United States of America, and a resident of New York city, county and State of New York, have invented certain new and useful Improvements in Turbines or Impact-Engines, of which the following is a specification, reference being had to the accompanying drawings, forming a part thereof.

My invention relates to turbine or rotary impact engines and its object is to cause the development of an increased driving power or impetus in the motive fluid by a novel method whereby a higher efficiency is attained. Furthermore, the principle employed in attaining such increased efficiency is here embodied in a manner not to impair the initial working value of the motive fluid but, on the contrary, to assist the fluid in its action throughout.

Referring to the drawings:

Figure 1 is a view in central transverse section through an engine embodying my invention and constructed to be operated in accordance with its novel method.

Fig. 2 is a sectional side elevation of the device shown in Fig. 1, the section being through the center of the latter figure.

Fig. 3 is a transverse sectional view through the buckets of the impelling wheel and the stationary abutments through which the motive fluid is admitted thereto, said view corresponding to a development of a plane through the center of the buckets.

Fig. 4 is an enlarged, partial longitudinal view taken on line 4-4 of Fig. 1, showing certain of the fluid passages in detail.

The engine here shown as one embodiment of my invention is of the single stage type, wherein the motive fluid acts successively or in a progressive manner upon the rotor or impelling wheel. In general, it comprises a suitable casing composed of a body portion 20 and the end heads 21-21' inclosing the rotor or impelling wheel 22 which is mounted on a central shaft 25. This shaft is journaled on oppositely arranged ball-bearings 26-26', complementary ball races therefore being arranged respectively on the shaft 25 and in the hangers 27-27' secured on the end plates 21-21' respectively. Within the hanger 27' at the left hand side of the engine, suitable ball-bearings 29-29 on oppo-

site sides of a collar 29' which is affixed to the shaft 25, are arranged to oppose end thrust of the shaft in each direction. The engagement of the central bearing flange of the impelling wheel with the end plates secures said wheel against any sidewise movement. 30-30 are stuffing box bushings fitted between the end plates and the shaft and arranged to leave inner packing spaces 31-31 around the shaft between them and the end plates.

The rotor comprises a central hub member 22' on the periphery of which is secured by keys 32, a central annular member 33 and outer annular members 34 and 35. The adjacent faces of these members are recessed to form between them two parallel sided annular grooves 36 and 37. The sides of these members which are thus recessed to form the sides of these grooves are also constructed with a series of lateral depressions 38 which form buckets for receiving the motive fluid and providing impact surfaces against which the motive fluid acts to impart its energy to the rotor. Thus the central member 33 is provided with buckets on both of its sides and the outer members are provided with similar buckets on their inner sides only. It is to be noted that the buckets are not as deep as are the annular grooves 36-37. These three members are fastened together with the buckets on the outer members opposite one another, but with the buckets on the central member offset from those on the outer members, and form the rotor ring of the apparatus. The buckets thus formed in the central member extend out to the periphery of this member, but those on the outer members although extending to the same distance from the axis of the shaft are shorter, and portions 39 of these members extend inward to the annular grooves 36-37.

The inner periphery 40 of the casing has a cylindrical bore of substantially the same diameter as that of the rotor ring. At equal distances about this periphery it is cut away and arranged to receive three stationary heads 41, the greater portions of which form continuations of the bore of the lining. Secured to these heads and projecting inwardly therefrom into the grooves 36-37 are stationary abutment plates 42-43, two from each of the heads 41. The rear end of each of these plates forms an edge 44 inclined

at an angle to the direction of rotation of the rotor ring and to the edges of the buckets therein. The front of each plate is a radial edge 45 formed by the sides of the plate converging toward a center. The function of these abutment plates is the same in each instance and therefore it will be sufficient for a proper understanding of this embodiment to explain the operation with regard to one of said heads and its attached abutment plates.

Each of the heads 41 is provided with a fluid inlet 46 which communicates with an expansion nozzle 47 through which motive fluid is directed at an angle to the periphery of the rotor ring. By means of the throttle valves 48 the nozzles are conveniently controlled to regulate the volume of the motive fluid supplied. The motive fluid introduced through the nozzle 47 passes directly to the buckets on either side of the central member 33 of the rotor ring as they pass beneath it. The motive fluid will impinge against the forward walls of the buckets whereby a portion of the energy of the fluid will be imparted to the impelling wheel to rotate it in the direction of the arrow in Fig. 1.

Referring now to Fig. 3 it may be seen that the motive fluid will pass from the buckets in the ring 33 through openings 49 in the plates 42-43, through which it is further expanded. These openings are preferably positioned adjacent to the nozzle and are arranged obliquely through the plates so that the motive fluid is directed against the forward walls of the opposed buckets respectively in the rings 34 and 35, thus producing a further impulse upon the impelling wheel as will be readily understood. In the position of the parts shown in Fig. 3 the motive fluid will pass thence through lateral recesses 50 provided in the plates 42-43, to the buckets in the rings 34-35 respectively in advance of those in line with the oblique openings 50, the shape of the recesses being such as to redirect the motive fluid against the walls of the buckets in the rings 34-35 upon which it will now act expansively, and thereafter the motive fluid will pass in front of the edges 45 of the plates to the grooves 36-37 in advance of the plates.

In the passage of the fluid through the grooves in advance of the plates 42-43, the fluid will travel with the impelling wheel but at a greater speed than the wheel, and by its engagement with the forward walls of the buckets will impart further energy thereto. As has been pointed out, the buckets in the adjacent rings are arranged in a staggered relation, so that this passage for the motive fluid is a zig-zag path which tends to increase the impelling effect of the motive fluid upon the rotor ring as the fluid

passes around the engine. As shown in Figs. 1 and 2 the fluid after it has expended the greater portion of its energy will pass from said grooves (assisted by the inclination of the rear edges 44 of the next pair of plates 42-43) to either side of the rotor through exhaust outlets 51 formed in the heads 41 which conduct the fluid to the exhaust chambers 52 from whence it passes through the usual exhaust outlets 58-59. 75

This invention includes the introduction and admixture of a comparatively heavy fluid, such as water, into and with the motive fluid which is preferably steam under pressure. This, by reason of its greater weight increases the momentum of the driving fluid and has other attendant advantages which I will set forth.

A simple way of accomplishing these results is clearly shown in Figs. 1, 3, and 4 of 85 the drawings. From these it may be seen that holes 54 are drilled through the plates 42 and 43 near the front edges 45 thereof preferably parallel with these edges and with the sides of the plates. Supply pipes 90 55 are connected with these holes and slits 56 are cut through the edges 45 into the holes 54.

Between the edges 45 of the stationary plates and the exhaust passages 51, the periphery of the lining 40 is shown cut away at 57 on a curve of comparatively small radius. A similar pocket cut in a slightly larger radius and of larger size is shown at 58, and a still larger pocket cut on a larger 100 radius at 59. Beyond this pocket and at the beginning of the exhaust chamber 51 another water supply pipe 60 may be provided. It is to be understood that this arrangement of pockets and water pipe is to be duplicated 105 between each inlet nozzle and its respective exhaust.

The operation of this part of the apparatus is as follows: When motive fluid, such as steam, is passing through the nozzles 47, 110 impact blades 42-43 and the annular zig-zag channels between the members of the rotor ring, and a heavier fluid such as water is admitted to these channels through the slits 56, the two fluids become mixed and pass through the channels together. The effect of the heavier liquid is to increase the momentum of the impelling medium. Another effect if steam and water are used is that some condensation takes place which 120 increases the velocity of the fluid. Moreover, I have found that wet steam has more efficiency in carrying the moving parts of the apparatus along with it than does dry steam. 125

There is of course a tendency of the heavier particles to be driven outwardly by centrifugal force and some of them will therefore enter the pockets 57-58-59. The curvature of these pockets will redirect such 130

5 particles down into the grooves 36—37 and the buckets 38. These pockets are of progressively larger size to provide for the expansion of the fluid as it passes through the engine.

10 If the pipes 60 are used cold water may be introduced through them near the point of exhaust. This will cause condensation and a consequent drop in pressure which will tend to increase the velocity of the steam through the engine and to utilize it to the fullest extent, thereby further increasing the efficiency of the apparatus.

15 Obviously this same method of condensing the steam may be used in other forms of engine than that shown herein.

What I claim is:

1. A rotary impact engine having a casing, a rotor within the casing arranged therewith to provide a substantially annular working passage for the motive fluid, stationary means for dividing said passage into a plurality of circumferential passages, means for introducing steam into said 25 passages at a given point on the periphery, and other means in advance thereof for commingling a jet of water with the steam flowing through said passages.

2. A rotary impact engine having a casing, a rotor within the casing arranged therewith to provide a substantially annular working passage for the motive fluid, stationary means for dividing said working passage into a plurality of circumferential passages, said casing being constructed to form a peripheral pocket having a curved face adapted to direct back into one of said circumferential passages such of the motive fluid as is thrown outward therefrom by 40 centrifugal force, and inlet and exhaust passages for the motive fluid.

3. A rotary impact engine having a casing, a rotor within the casing arranged therewith to provide a substantially annular working passage for the motive fluid, stationary means for dividing said working passage into a plurality of circumferential passages, said rotor being provided with radially disposed depressions offset 50 from one another to thereby make the side walls of said passage tortuous, said casing being constructed to form a plurality of peripheral pockets of successively increasing size, said pockets having curved faces adapted to direct back into said circumferential passage such of the motive fluids as are thrown outward therefrom by centrifugal force, and inlet and exhaust passages for the motive fluid.

60 4. A rotary impact engine having a casing, a rotor within the casing arranged therewith to provide a substantially annular working passage for the motive fluid, means for introducing the motive fluid into said passage, other means in advance there-

of for introducing a heavier fluid into the passage, said casing being constructed to form a peripheral pocket having a curved face adapted to direct back into said passage such of the fluid as is thrown outward by 70 centrifugal force, and means for leading exhaust fluids from said passage.

5. A rotary impact engine having a casing, a rotor within the casing arranged therewith to provide a substantially annular working passage for the motive fluid, means for introducing steam under pressure into said passage, other means in advance thereof for introducing water into the passage, the rotor being provided with 75 radially disposed depressions offset from one another to thereby make the side walls of said passage tortuous, said casing being constructed to form a plurality of peripheral pockets of successively increasing size, 80 said pockets having curved faces adapted to direct back into said passage such of the fluids as are thrown outward by centrifugal force, the casing being also constructed to form an exhaust passage, and a water inlet 90 pipe near such exhaust passage.

6. In a rotary impact engine, a casing having a cylindrical bore, a rotor comprising three rings recessed to form annular channels between them, the adjacent faces 95 of said rings being provided with depressions forming radially disposed buckets, a pair of stationary plates each projecting into and inclosing a part of one of said channels, said plates having their sides converging to a reduced front edge, the edge of each plate being cut to form a slit, and means for passing a fluid heavier than the motive fluid into the channels through said slits, means for admitting motive fluid 100 through the casing into the channels back of said slits, the back of said plate being arranged at an angle to the buckets to deflect the motive fluid outward, the casing being constructed to form an exhaust passage. 105

7. In a rotary impact engine, a casing having a cylindrical bore, a rotor comprising three rings recessed to form annular channels between them, the adjacent faces of said rings being provided with depressions forming radially disposed buckets, a pair of stationary plates each projecting into and inclosing a part of one of said channels, said plates having transverse oblique openings therethrough and having 110 their sides converging to a reduced front edge, the edge of each plate being cut to form a slit, and means for passing a fluid heavier than the motive fluid into the channels through said slits, means for admitting motive fluid through the casing into the channels back of said slits, the openings through the plates being arranged to constitute a passage through which the motive fluid will pass from the buckets in one of the 115 120 125 130

rings to the buckets in the other rings and beyond said plate through the channels, the back of said plate being arranged at an angle to the buckets to deflect the motive fluid outward, the casing being constructed to form an exhaust passage, and a water inlet pipe near said exhaust passage.

Copies of this patent may be obtained for five cents each, by addressing the "Commissioner of Patents, Washington, D. C."

In witness whereof I have hereunto set my hand this 26th day of October, 1911.

EMIL ANDERSON.
